INVENTOR

UNITED STATES PATENT OFFICE.

JACOB FELBEL, OF NEW YORK, N. Y.

DESIGN FOR A TYPE-WRITING-MACHINE TOP PLATE.

SPECIFICATION forming part of Design No. 32,687, dated May 22, 1900.

Application filed April 23, 1900. Serial No. 14,048. Term of patent 14 years.

To all whom it may concern:

Be it known that I, JACOB FELBEL, a citizen of the United States, and a resident of the borough of Manhattan, city of New York, in the county of New York and State of New York, have invented a certain new and original Design for a Type-Writing-Machine Top Plate, of which the following is a specification.

Figure 1 is a perspective view of a top plate 10 for a type-writing machine, showing my new design. Fig. 2 is a sectional view taken at the line Y Y of Fig. 1, and Fig. 3 is a sectional view taken at the line X X of Fig. 1.

The top plate comprises a broad section 15 A, extending from right to left, and two forwardly-extending end members B and C. Between the members B and C is a wide space or break (indicated at D) which extends back to the forward edge of the member A, thus 20 giving the plate a bifurcated appearance at

its front side. The corners of the free ends of the parts B and C are curved or rounded, and the several members are finished with a short depending flange or apron. The bifurcated front portion of the plate is the leading 25 feature of my design.

Having described my invention, what I claim as new, and desire to secure by Letters Patent, is—

The design for the top plate of a type-writing machine, substantially as herein shown and described.

Signed at the borough of Manhattan, city of New York, in the county of New York and State of New York, this 21st day of April, 35 A. D. 1900.

JACOB FELBEL.
